UNITED STATES PATENT OFFICE.

LOUIS M. ASPINWALL, OF PITTSBURGH, AND HARRY R. MEYER, OF WILKINSBURG, PENNSYLVANIA, ASSIGNORS TO WESTINGHOUSE ELECTRIC & MANUFACTURING COMPANY, A CORPORATION OF PENNSYLVANIA.

CONTROL APPARATUS.

Application filed November 3, 1919. Serial No. 335,492.

Our invention relates to control apparatus and it has special relation to the mechanical interlocking of drum controllers to prevent false operation.

5 The object of our invention is to provide a control apparatus embodying a drum controller and a foot-operated switching device, together with means for interlocking the control drum and the switching device 10 to prevent undesirable relative movement of the two members.

More specifically stated, it is an object of our invention to provide a plural-position foot-operated switching device so interlocked with a control drum that movement of the drum to an operative position is prevented unless the foot-operated switching device has been opened.

From another angle, it is an object of our 20 invention to interlock the above-mentioned control drum and foot-operated switching device so that the drum may be moved to a dynamic-braking position only when the switching device occupies an open or inoperative position.

Another object of our invention is to provide a quick-operating mechanism that is associated with the above-mentioned foot-operated switching device in order to afford relatively rapid closing and opening 30 of the circuit.

Other objects of our invention will become evident from the following detailed 35 description, taken in conjunction with the accompanying drawings, wherein

Fig. 1 is a view, in front elevation, of a control apparatus constructed in accordance with our present invention;

40 Fig. 2 is a plan view of a portion of the apparatus that is shown in Fig. 1; and

Fig. 3 to Fig. 9, inclusive, are detail elevational views illustrating various operating members of the apparatus that is shown in the preceding figures.

45 Referring to the drawings, the structure here shown comprises a drum controller having a rear plate or frame 1 and a curved front cover or encasing member 1a for enclosing a control drum 2 that is provided with an operating shaft 3, a finger-base 4 for the drum, and a foot-operated switch-

ing and interlocking device 5 which is actuated through the agency of a pedal mechanism 6 outside of the controller case.

The lower end of the control drum 2 is 55 supported in a suitable journal 7, and a collar 8 is secured to the shaft 3 below the drum 2 for the purpose of assisting to properly positon the interlocking device 5.

A notched member or star-wheel 9, of a 60 familiar general form, is rigidly secured to the operating shaft 3 near its lower end and is provided with a plurality of recesses or notches 10 to 16, inclusive, that respectively correspond to the several positions of the 65 control drum 2. The notches 10 and 16, respectively corresponding to the "off" and the "dynamic-braking" positions, are relatively shallow for interlocking purposes to be set forth, while the remaining notches 70 are comparatively deep. The electrical circuits governed by the control drum 2 and the foot-operated switching device 5 constitute no part of our present invention, but are fully set forth and claimed in a copending application of B. O. Austin, Serial No. 723,847, filed Oct. 6, 1919, and assigned to the Westinghouse Electric & Manufacturing Company.

75 Notches 11, 12 and 13 thus correspond to "forward" operation of the motors to be controlled, while notches 14 and 15 correspond to "reverse" operation. The "dynamic-braking" notch 16 follows the "reverse" notch 15, since the motors necessarily are reversed before dynamic-braking operation can be set up, as is well known.

80 Loosely enclosing the operating shaft 3, between the star-wheel 9 and the collar 8, is a portion of the interlocking device 5 90 comprising a metallic disk or cam 20, having a hub 20a, and an arm or lever 21 of bakelized micarta or other similar insulating material which is secured to the disk 20 by means of a plurality of screws 22. One side of the cam 20 is provided with a projecting lug 23 and a notch 24 adjacent thereto for interlocking purposes to be set forth. The opposite end of the lever 21 has attached thereto, by means of a bolt 25, a 95 bridging contact member 25a having contact tips 26 and 26a for engaging a pair of 100

spaced stationary contact members 27 and 27a. The stationary contact members are suitably secured to bent straps or supports 28 and 28a which are mounted upon an insulating block 29 that is secured to the rear plate 1 by means of a plurality of tap bolts 30. For the purpose of connecting the stationary contact members 27 and 27a to an external circuit, a pair of suitable wire-receiving terminals or sockets 31 and 32 are bolted to the supporting members 28 and 28a.

10 A flat ring 36 (see also Fig. 8 and Fig. 9) of smaller diameter than the disk 20 is loosely or pivotally fastened, by a small bolt 37, to the switch lever 21. At a point diametrically opposite the mechanical connection 37, a boss or stud 38 is located for the purpose of supporting one end of a spiral spring 39, the other end of which is secured to a rocking lever or crank arm 40, which is also shown in Fig. 6 and Fig. 7. The lower apertured end of the arm 40 is rigidly attached to a short shaft 41 that passes through a boss 42 which is secured to the rear plate 1 of the controller. A metallic lever or rod 43 is rigidly secured to the outer end of the shaft 41 to the rear of the controller case and is mechanically connected to the pedal mechanism 6, as more fully hereinafter described.

15 In order to mutually interlock the star-wheel 9 and the switch lever 21, whereby undesirable relative movement of the control drum 2 and the foot-operated switching device 5 may be prevented, a pawl member 44 is provided, the structural details of which are illustrated in Fig. 3 to Fig. 5, inclusive.

20 The pawl 44 comprises a base or arm 44a upon one end of which a roller 45 is loosely mounted for the purpose of engaging the various notches 10 to 16, inclusive, in the star-wheel 9. A spacing block 46 is secured, by rivets 46a, to the opposite end of the arm 44a, and an interlocking lever 47 is located above the block 46, extending at substantially right angles to the arm 44a, and is held in position by the same securing means. A bolt-hole 48 is provided to permit loose or pivotal attachment of the pawl 44 to a lug 49 upon the inside of the rear plate 1 by means of a bolt 49a. A boss or protuberance 50 on one edge of the arm 44a is provided for the purpose of positioning one end of a biasing spring 51, the other end of which is suitably associated with the rear plate 1, whereby the pawl 44 is biased toward a position of engagement with the notches in the star-wheel 9.

25 For the purpose of biasing the pedal mechanism 6 to a position corresponding to the open-circuit condition of the switching device 5, a helical spring 56, or the equivalent, may be provided. The lower end of the spring 56 is hooked through an opening

57 in the rod or lever 43, while the upper end of the spring passes over a suitable boss or lug 58 on the outside of the rear plate 1.

The free end 59 of the lever 43 is slotted to engage one end of a link or clevis 60, whereby a suitable lost-motion connection is provided between the lever 43 and the pedal mechanism 6. The mechanism 6 is shown as comprising a pedal or foot-lever 61 which has a detachable hook connection 62 with one end of the link or clevis 60, and the underside of the pedal 61 is provided with a pair of depending lugs or arms 63 for partially enclosing a pin or pivot 64. The pin 64 is supported by a pair of standards or brackets 66 that are integrally associated with a suitable base 67. A plurality of bolts 68 may be employed to secure the base 67 in the desired location. By reason of the illustrated pivotal construction of the pedal 61, the pedal may be removed, when desired, for operation at the other end of the vehicle and to prevent unauthorized movement of the mechanism.

30 The control drum 2 is illustrated as occupying its initial position in the forward direction or, in other words, the roller 45 of the pawl 44 engages the notch 11 while the foot-operated switching device 5 is shown as occupying its closed position, wherein the contact members 26 and 27, for example, are in engagement. The operation of our controlling and interlocking device, under such conditions, may be set forth as follows. If it is attempted to move the control drum 2 backwardly to the "off" position, corresponding to the engagement of roller 45 and notch 10, such action cannot be effected so long as the foot-operated switching device 5 remains closed, since the roller 45 cannot pass over the ridge between the notches 11 and 10 by reason of the fact that the interlocking arm 47 strikes the adjacent portion of the switch cam 20. Consequently, the control drum 1 cannot be returned to its "off" position until the pedal mechanism 6 is released by the operator removing his foot, whereupon, the spring 56 will return the connected members to their normal or biased positions and, in particular, the short shaft 41 and the crank arm 40 will be rotated clockwise. As soon as the line of action of the spring 39 passes beyond the dead-center position, with respect to the switch arm 21, namely, beyond a line passing through the pivotal point 37 and the axis of the operating shaft 3, the foot-operated switching device 5 will be quickly opened.

35 The extreme open position of the switching device 5 is determined by the engagement of the lug 23 on the switch arm 21 with the interlocking pawl arm 47. In that case, the desired backward movement of the control drum 2 may be effected.

40 When the control drum 2 is moved to its

"off" position corresponding to the engagement of roller 45 and notch 10, the switching device 5 being open, the pawl arm 44a is actuated in opposition to the coil 5 spring 51, and the interlocking arm 47 is rotated clockwise, when viewed from above, being guided, by the lug 23, into a position of engagement with the notch 24 in the switch cam 20. Consequently, movement of 10 the switching device 5 into its illustrated operative position is prevented, since the cam 20 cannot be moved so long as the interlocking arm 47 engages the notch 24. However, the control drum may be moved to any 15 other position to set up the desired motor connections. In that case, unless the "dynamic-braking" position, corresponding to shallow notch 16, has been selected, the foot-operated switching device may be closed as 20 follows. Upon the application of downward pressure to the toe of the pedal 61, the lever arm 43 is depressed in opposition to the action of the biasing spring 56, the shaft 41 and the crank arm 40 are rotated in a 25 counter-clockwise direction, and the switching device 5 is quickly actuated to its illustrated closed position as soon as the line of action of the spring 39 passes beyond the above-mentioned dead-center position.

Consequently, the mechanical interlocking that we provide prevents the control drum 2 from either opening or closing the electric circuit, and all such making and breaking of the circuit is accomplished by the foot-operated switching device 5.

Further interlocking of the control drum and the foot-operated switching device is provided in the "dynamic-braking" position of the control drum, corresponding to shallow notch 16. It will be appreciated that, whenever the motor circuits are to be reorganized for dynamic braking, the connection of the motors to the supply circuit should be maintained open. This function is assured by the operation of our mechanism, since the roller 45 of the pawl 44 cannot pass over the ridge between notches 15 and 16 when the switching device occupies its illustrated closed position, because, in 50 that case, the interlocking arm 47 engages the adjacent portion of the switch cam 20 and the attempted rotative movement of the control drum is precluded. However, upon release of the pedal mechanism 6 to effect the above-mentioned quick-opening movement of the switching device 5, the interlocking arm 47 is then located opposite the peripheral notch 24 in the switch cam 20 and, therefore, movement of the control drum to 55 its "dynamic-braking" position, corresponding to the engagement of roller 45 and notch 16, is permitted. In this way, dynamic braking circuits cannot be set up unless the line or supply-circuit connection of the motors has previously been interrupted.

In other words, the foot-operated switching device 5 cannot be closed when the control drum occupies either its "off" or its "dynamic-braking" position, since the interlocking arm 47 is prevented from clearing 70 the notch 24 by reason of the provision of the shallow notches 10 and 16 in the star-wheel 9.

We do not wish to be restricted to the specific structural details or arrangement of 75 parts herein set forth, as various modifications thereof may be made without departing from the spirit and scope of our invention. We desire, therefore, that only such limitations shall be imposed thereon as are 80 indicated in the appended claims.

We claim as our invention:

1. Control apparatus comprising two transversely-related shafts, a switch member and a star-wheel respectively loosely and 85 rigidly mounted on one of said shafts, a crank arm rigidly secured to the other shaft, an interlocking pawl between said star-wheel and said switch member, and a flexible connection between said switch member and said 90 crank arm.

2. Control apparatus comprising two transversely-related shafts, a switch member and a star-wheel respectively loosely and 95 rigidly mounted on one of said shafts, a crank arm rigidly secured to the other shaft, an interlocking pawl between said star-wheel and said switch member, a ring enclosing one of said shafts and having one point 100 loosely secured to said switch member, and a spring for connecting a diametrically opposite point in said ring to said crank arm.

3. In a controller, in combination, a drum shaft, a star wheel mounted on the shaft, a switch member loosely mounted on said shaft and disposed for movement relative to the star wheel, means for actuating the switch member independently of the star wheel, a spring-pressed pawl interposed between the star wheel and switch member, 105 said star wheel being adapted when moved to a predetermined position to actuate the pawl to lock the switch member.

4. In a controller, in combination, a drum shaft, a star wheel mounted on the shaft, a switch member loosely mounted on said shaft and disposed for movement relative to the star wheel, means for actuating the switch member independently of the star wheel, a 115 spring-pressed pawl interposed between the star wheel and switch member, said switch member and star wheel being adapted to cooperate when in predetermined positions 120 to restrict the movement of one another, and means adapted to limit, independently of the star wheel, the operation of the switch member in one direction.

5. In a controller, in combination, a drum shaft, a star wheel mounted on the shaft, a 130 switch member loosely mounted on said shaft

and disposed for movement relative to the star wheel, means for actuating the switch member independently of the star wheel, a spring-pressed pawl interposed between the star wheel and switch member, the switch member having a notch therein to receive an end of the pawl, said star wheel being provided with a projection adapted to actuate the pawl to engage in said notch, thereby to lock the switch member.

6. In a controller, in combination, a drum shaft, a star wheel fixed to said shaft, a switch member loosely mounted on said shaft and rotatably mounted on the shaft, means for actuating the switch member independently of the star wheel, a spring-

pressed pawl interposed between the star wheel and the switch member, the spring serving to retain the pawl continuously in engagement with the star wheel, said switch member having a notch therein to receive one end of the pawl, an indented projection formed on the star wheel for operating the pawl to engage in the notch to lock the switch member and means carried by the switch cooperative to limit its angular movement in one direction.

In testimony whereof, we have hereunto subscribed our names this 27th day of Oct., 1919.

LOUIS M. ASPINWALL.
HARRY R. MEYER.
